UNITED STATES PATENT OFFICE.

ZÉPHIRIN LAMBERT, OF GRAND MÈRE, QUEBEC, CANADA, ASSIGNOR TO J. E. McLAUGHLIN, OF GRAND MÈRE, QUEBEC, CANADA.

PNEUMATIC DRILL.

1,339,565.

Specification of Letters Patent. Patented May 11, 1920.

Application filed March 20, 1918. Serial No. 223,559.

To all whom it may concern:

Be it known that I, ZÉPHIRIN LAMBERT, a subject of the King of Great Britain, residing at Grand Mère, Province of Quebec, 5 Canada, have invented certain new and useful Improvements in Pneumatic Drills; and I do hereby declare that the following is a full, clear, and exact description of the invention, such as will enable others skilled 10 in the art to which it appertains to make and use the same.

The present invention relates to drills and more particularly to devices of this character which are equipped with a motor for 15 driving the drill, and an object of the present invention is to provide a pneumatic motor attachment for drills which can be easily and readily installed and transported from place to place.

20 A further object of the present invention is to provide a device of this character wherein the several parts thereof may be readily assembled or disassembled for replacing worn parts and one which will be 25 efficient and durable in operation.

With the above and other objects in view which will hereinafter appear as the description continues, the invention consists 30 of the novel features of construction, combination and formation of parts as will be hereinafter more fully described and particularly pointed out in the appended claims.

In the accompanying drawings has been 35 shown a simple and preferred form of the invention, it being, however, understood that no limitation is necessarily made to the precise structural details herein exhibited, but the right is hereby reserved to any 40 changes, alterations or modifications to which recourse may be had that come within the scope of the claims without departing from the spirit of the invention or sacrificing the efficiency of the same.

45 In the accompanying drawings:

Figure 1 is a side elevation of one form of the device embodying the present invention;

Fig. 2 is a horizontal section through the 50 same;

Fig. 3 is a detail sectional view of the rotor;

Fig. 4 is a vertical section through a slightly modified form of the invention;

Fig. 5 is a detail sectional view of the 55 controlling valve;

Fig. 6 is a side elevation of another slightly modified form of the invention; and,

Fig. 7 is a vertical transverse section 60 through the same.

Referring now more particularly to the accompanying drawings wherein like and corresponding parts are designated by similar reference characters throughout the several views,

The drill as shown in Figs. 1 and 2 of the drawings comprises a casing 1 preferably made of cast iron having a cover 2 and a depending bearing portion 3. Eccentrically 70 arranged within the casing 1 and journaled within the bearings 3 and 4 is a shaft carrying a rotor 5 and connected to the lower end of this shaft is a drill-chuck 6 whereby different sized drills may be readily connected 75 or disconnected. Seated within the casing 1 is a removable ring 7 preferably made of bronze and is so mounted within the casing that it may be easily and readily removed so that a new one may be substituted therefor 80 when it becomes worn or broken. This bearing ring 7 constitutes a main constructional element of the whole device herein described. Formed with it are oppositely disposed 85 openings adapted to be engaged by the inlet and outlet conduits of the motor. Another opening is also formed within said ring and is adapted to be engaged by the auxiliary exhaust or outlet conduit 24.

Now, taking the ring as a basis for assembling the different parts of the machine together:—1st, The casing 1 is adapted on the outer periphery of said ring, care being taken to have the openings in said ring coincide with those correspondingly formed 90 within the casing. The inlet and exhaust conduits are then connected and adjusted so as to engage said openings. Finally, the rotary piston 5 with its depending propeller blades 22 and piston rod 44 is eccentrically mounted within the ring, and, the cover 2 then being properly adjusted over the opening, the device is ready for action. When it is in operation the thrust of the piston rod is totally taken up and provided 95 for by an end thrust bearing 29, as described herein, within which is journaled and pivotally mounted the portion of the piston rod 100 105

- projecting out from the lateral face of piston and oppositely located to the portion of said piston rod journaled within bearing 3 and adapted for action with the drill-chuck.
- 5 Said end thrust bearing may be provided with ball bearings or other similar means for reducing frictional contact. Also formed with the casing 1 are the internally threaded projections 8 and 9 respectively.
- 10 Connected to the projection 8 is an inlet pipe 10 which supplies air under pressure to the casing 1 for driving the rotor 5. This inlet pipe 10, as better shown in Fig. 5 of the drawings, has arranged therein a partition 11 for dividing the inlet pipe into the sections 12 and 13. Communicating with the sections 12 and 13 are the ports 14 and the latter being formed within the pipe 10. Slidably mounted upon the pipe 10 is a tubular sleeve 15 and the outer periphery of this sleeve is milled so as to provide a handle. The inner periphery of this sleeve 15 has formed a recess 16 which is adapted to bring the ports 14 into communication therewith. Formed within the sleeve 15 is a diagonal arcuate slot 17 and extending through this slot is a set screw 18 and the latter is permanently fixed within the pipe 10. From this it is obvious that by turning the sleeve 15 the ports 14 will be brought into communication, so that the air under pressure may be supplied to the motor and when these ports 14 are brought into communication the sleeve 15 assumes the position as better illustrated in Fig. 2. By sliding and turning the sleeve upon the pipe 10 it will assume the position as better shown in Fig. 5, wherein the ports 14 are out of communication and the air supplied to the motor is cut off. The sliding and rotary movement of the sleeve 15 is limited by means of the slot and screw connection 17 and 18 respectively.

Leading from the projection 9 is an exhaust pipe 19 and encircling this exhaust pipe is a handle 20 which also has its outer periphery milled as better shown in Fig. 1. The outlet end of the pipe 19 is provided with a perforated partition 21 whereby the exhaust air will be split up and muffed before entering the atmosphere.

The rotor 5 is provided with a plurality of radial slots and slidably mounted within each of these slots is a blade 22. These blades 22 are normally retained in an expandible position by means of the coil springs 23 as shown in Fig. 3 of the drawings. As the air under pressure enters the casing 1 it strikes against the blade 22 thereby causing the rotor 5 to move and subsequently the air will exhaust through the exhaust pipe 19. Due to the great speed of the rotor 5 a considerable amount of the air within the casing 1 has not time enough to pass into the pipe 19, and therefore I pro-

vide an auxiliary exhaust 24. This auxiliary exhaust may be eliminated by providing a groove within the inner periphery of the ring 7 and this groove communicating with the pipe 19 so that the air may escape 70 totally through the pipe 19. By increasing or decreasing the size of this auxiliary outlet 24 the speed of the rotor may be controlled.

From the foregoing it is obvious that by 75 grasping the handles 15 and 20 the drill may be readily placed upon its work and the motor will be absolutely under control of the operator by turning the handle 15. Therefore no valves are necessary for regulating 80 the supply of compressed air to the motor.

Referring to Fig. 4 of the drawings, I have illustrated a slightly modified form of the invention whereby it is desired to reduce the number of revolutions per minute of the 85 drill, so that the strength of the drill will be greatly increased. The casing 1 is slightly increased in height and has formed therein a partition 25 and upon this partition the rotor 5 is mounted. The cover 26 is provided with a depending flange 27 which is in threaded engagement with the casing 1 and acts in the same capacity as the ring 7. The shaft 28 of the rotor is journaled within the partition 25 and has a detachable thrust 90 bearing 29 which is retained within the internally threaded projection 30 of the cover 26. The outer periphery of this projection 30 is also threaded so that a suitable handle may be connected thereto when it is desired 100 to apply pressure in a vertical direction upon the drill. The lower end of the shaft 28 has connected thereto a pinion 31 and this pinion is adapted to mesh with a larger gear wheel 32 keyed to the vertical shaft 33 and 105 the latter being journaled within the partition 25 and the bottom 34 of the casing 1. Also carried by the shaft 33 is a pinion 35 which is adapted to mesh with a gear 36 and the latter is carried by the shaft 37 to which 110 is connected the drill-chuck 6.

From this construction it will be apparent that as compressed air enters the casing 1 the rotor will be caused to rotate and in turn the drill-chuck 6 will be rotated at a very 115 much reduced speed.

In the form of the invention as shown in Figs. 6 and 7 of the drawings, I have illustrated wherein this device may be applied to a stationary support. A suitable base or 120 platform 38 is herein shown and connected to this base is an internally threaded projection similar to the projection 9 as shown in Fig. 1 and which is indicated by the numeral 39. Also extending through this base is the 125 exhaust pipe 40. The casing 1 is then supported upon this base 38, but the shaft 41 which is connected to the rotor 5 projects beyond both sides of the casing 1 and may have connected thereto emery wheels 42 as 130

shown, or any other suitable devices which require rotation.

From this construction it is obvious that the device may be mounted upon a stationary support, or it may be transported when desired and manually controlled.

Having thus fully described my invention, what I claim as new and desire to secure by Letters Patent is:

- 10 1. The combination with a pneumatically driven rotary motor, comprising a cylindrical casing open at one end, a bearing portion for one end of piston rod eccentrically formed with the closed end of said casing, 35 a cover having formed therewith a bearing portion for the other end of said piston rod, diametrically opposed hollow projections formed with said cylindrical casing and adapted for connection, on the one hand, 40 with an inlet air pipe provided with valve means for regulating the flow of motive fluid within the motor, on the other hand, with an exhaust pipe, an auxiliary outlet air exhaust, a rotary piston carrying slidable propeller 45 blades, said piston rigidly mounted on a rod or shaft, an anti-friction metal bearing ring to which adhere all other parts composing the device herein described, of an end thrust bearing adapted for location and 50 adjustment within the projection eccentrically formed with the cover of said device, said bearing being susceptible to regulation by hand so as to effectively and totally take up the thrust of the piston rod at any time 55 when said device is in operation.
- 15 2. The combination with a pneumatically driven motor, comprising a cylindrical casing open at one end, a bearing portion for one end of piston rod eccentrically formed with the closed end of said casing, 35 a cover having formed therewith a bearing portion for the other end of said piston rod, diametrically opposed hollow projections formed with said cylindrical casing and adapted for connection, on the one hand, 40 with an inlet air pipe provided with valve means for regulating the flow of motive fluid within the motor, on the other hand, with an exhaust pipe, an auxiliary outlet air exhaust, a rotary piston carrying slidable propeller 45 blades, said piston rigidly mounted on a rod or shaft, an anti-friction metal bearing ring to which adhere all other parts composing the device herein described, of an end thrust bearing adapted for location and 50 adjustment within the projection eccentrically formed with the cover of said device, said bearing being susceptible to regulation by hand so as to effectively and totally take up the thrust of the piston rod at any time 55 when said device is in operation.
- 20 3. The combination with a pneumatically driven motor, comprising a cylindrical casing open at one end, a bearing portion for one end of piston rod eccentrically formed with the closed end of said casing, 35 a cover having formed therewith a bearing portion for the other end of said piston rod, diametrically opposed hollow projections formed with said cylindrical casing and adapted for connection, on the one hand, 40 with an inlet air pipe provided with valve means for regulating the flow of motive fluid within the motor, on the other hand, with an exhaust pipe, an auxiliary outlet air exhaust, a rotary piston carrying slidable propeller 45 blades, said piston rigidly mounted on a rod or shaft, an anti-friction metal bearing ring to which adhere all other parts composing the device herein described, of an end thrust bearing adapted for location and 50 adjustment within the projection eccentrically formed with the cover of said device, said bearing being susceptible to regulation by hand so as to effectively and totally take up the thrust of the piston rod at any time 55 when said device is in operation.
- 25 4. The combination with a pneumatically driven motor, comprising a cylindrical casing open at one end, a bearing portion for one end of piston rod eccentrically formed with the closed end of said casing, 35 a cover having formed therewith a bearing portion for the other end of said piston rod, diametrically opposed hollow projections formed with said cylindrical casing and adapted for connection, on the one hand, 40 with an inlet air pipe provided with valve means for regulating the flow of motive fluid within the motor, on the other hand, with an exhaust pipe, an auxiliary outlet air exhaust, a rotary piston carrying slidable propeller 45 blades, said piston rigidly mounted on a rod or shaft, an anti-friction metal bearing ring to which adhere all other parts composing the device herein described, of an end thrust bearing adapted for location and 50 adjustment within the projection eccentrically formed with the cover of said device, said bearing being susceptible to regulation by hand so as to effectively and totally take up the thrust of the piston rod at any time 55 when said device is in operation.
- 30 5. The combination with a pneumatically driven motor, comprising a cylindrical casing open at one end, a bearing portion for one end of piston rod eccentrically formed with the closed end of said casing, 35 a cover having formed therewith a bearing portion for the other end of said piston rod, diametrically opposed hollow projections formed with said cylindrical casing and adapted for connection, on the one hand, 40 with an inlet air pipe provided with valve means for regulating the flow of motive fluid within the motor, on the other hand, with an exhaust pipe, an auxiliary outlet air exhaust, a rotary piston carrying slidable propeller 45 blades, said piston rigidly mounted on a rod or shaft, an anti-friction metal bearing ring to which adhere all other parts composing the device herein described, of an end thrust bearing adapted for location and 50 adjustment within the projection eccentrically formed with the cover of said device, said bearing being susceptible to regulation by hand so as to effectively and totally take up the thrust of the piston rod at any time 55 when said device is in operation.

In witness whereof I have hereunto set my hand.

ZÉPHIRIN LAMBERT.
